UNITED STATES PATENT OFFICE.

JOEL C. WELLS, OF SOUTHERBRIDGE, MASSACHUSETTS.

SPECTACLES.

1,108,957.

Specification of Letters Patent.

Patented Sept. 1, 1914.

Application filed April 18, 1914. Serial No. 832,912.

To all whom it may concern:

Be it known that I, JOEL C. WELLS, a citizen of the United States, residing at Southbridge, in the county of Worcester and 5 State of Massachusetts, have invented certain new and useful Improvements in Spectacles, of which the following is a specification.

My invention relates to improvements in 10 spectacles and has particular reference to an improved type of mounting wherein the weight is carried on the nose by fixed supports located substantially in the line of the lenses and capable of ready adjustment to 15 the facial requirements of the wearer, and which is held from toppling by independent anchoring means.

The leading object of my invention is the 20 provision of a novel, attractive and commercially practical construction of the character above mentioned.

Among other objects of my invention are 25 the provision of an improved mounting of this type in which the various parts shall be detachably connected and of standard construction to permit of removal, replacement and interchangeability of the parts, as 30 desired; the provision of adjusting means whereby the supports and the anchoring 35 means may be easily conformed to the facial requirements of the wearer, and a simplification of construction whereby the various parts may be accommodated in minimum space and present the most attractive appearance.

Further objects and advantages of my 40 improvement should be readily apparent by reference to the following specification taken in connection with the accompanying drawings forming a part thereof, and it will be understood that I may make any modifications in the specific details of construction shown and described within the scope of the appended claims without departing from or 45 exceeding the spirit of my invention.

Figure I represents a front view of one 50 form of my invention. Fig. II represents a top plan view of the construction as illustrated in Fig. I. Fig. III represents a fragmentary perspective view showing the parts at one side of the mounting in disassembled relation. Fig. IV represents a sectional view on the line IV—IV of Fig. I. Fig. V represents a sectional view on the 55 line V—V of Fig. IV. Fig. VI represents a fragmentary plan view with parts removed. Fig. VII represents a view similar to Fig. V illustrating a modified construction. Fig. VIII represents a similar view of a slight modification. Fig. IX represents a similar view illustrating a different arrangement of the parts. Fig. X represents a similar sectional view showing another arrangement of the parts. Fig. XI represents a perspective view of a modified 60 construction of lower or rigid guard. Fig. XII illustrates a modified method of locking the stationary member in desired 65 adjusted position.

In the drawings, in which similar characters of reference are employed to denote corresponding parts throughout the several views, the numeral 1 designates the lenses secured within the clips 2 carried by the bridge 3, by screws or other customary lens 70 securing means 5.

In that form of my invention most clearly illustrated in Figs. III and V, I have shown as located at each side of the mounting, and forming a part of the bridge 3, a seat member 4, on which is mounted the extremity 6 of the guard 7, said extremity 6 having the notch 8 receiving a portion of the strap to facilitate locking of the guard against rotation. It will be understood, however, that other means of locking the guard may be employed, such as the prongs 9 fitting into sockets in the bridge, as shown in Fig. VII, the recessing of the bridge to receive the end of the guard, as illustrated in Fig. X, 90 the bending downward of the end of the guard to engage the supporting portion 4, as illustrated in Fig. XI, or the pin or lug and notches, as shown in Fig. XII, these being some of the other forms which can 95 be employed for this purpose. The pivot or securing screw 10 passes through the portion 6 of the guard into the support, while mounted on the pivot and bearing against one face of the guard 7 is the tube 100 11, the pivot 10 having a shoulder 12 bearing against the outer portion of the tube to securely force the same downward onto the guard to clamp the guard in position. Turning on the tube is a guard lever 13 105 having an operating portion 14 at one end and a looped portion 15 at the other terminating in an L, 16, a pad 17 being pref.

erably loosely mounted over the terminus of the L, 16, and may, if desired, be held from complete rotation by use of an elongated perforation and flattened stem, by a double pin or other securing device. I preferably form the tube as shown with a flange 18 bearing against the upper face of the lever to prevent weaving thereof, while mounted on the pivot above said flange is an actuating spring 19 for swinging the lever into clamping position, but it will be understood that if desired the shoulder of the screw may rest directly on the guard head 6 and the tube may be dispensed with.

In that form of my invention shown in Figs. VII and VIII, in addition to the head 6 being provided with the prongs 9 fitting into the bridge, I have placed said head on the under side instead of the upper side of the bridge or support 4, the fastener 10 either extending downward through said portion 4 and threading into the portion 6 of the guard 7 to tightly draw and hold the same against said member 4, as shown in Fig. VII, or a second screw 10' being employed, the latter being shown in Fig. VIII. In this form I have omitted the flanged tube, which may be employed or not, as mentioned in connection with the construction of Figs. III and V.

In Fig. IX, I have shown a reversal of the parts of my mounting, in that the spring is disposed on the upper side of the portion 4, the flanged tube bearing directly against the under side and providing a bearing for the lever arm, while the stationary guard 7 is clamped between the flange of the tube and the head of the screw, the construction of the parts being substantially the same as before illustrated.

Fig. X represents another slight modification of my idea, in which the screw has a shoulder bearing directly against the portion 6 of the guard 7 and clamping the same against the support, the lever swinging directly on the portion 6 and having the head of the fastener 10 bearing against the other surface thereof to prevent weaving, the fastener being continued below the support 4, if desired, to provide a guide for positioning of the actuating spring 19.

In Fig. XII in place of the head 6 having but a single notch, I have provided the support with the rib or pin 20 adapted to fit into any one of a plurality of notches 21, this facilitating adjustment of the guard 7 into desired position without undue twisting or bending of the reduced neck portion thereof.

In the use of any of the foregoing forms of my invention as illustrated and described, the general fitting and operation of the same are identical, that is, the pads 7 are adjusted to properly fit against the nose of the wearer and steady the mounting in po-

sition, it being understood that they may be so adjusted as to support the entire weight of the mounting or as to support but a part of said weight, the remainder if desired may be supported by the bridge which may be adjusted to exactly fit the crest of the nose, as may be deemed most advantageous by the fitter of the mounting. In any event, the bridge and lower bearing member or members, as the case may be, support the entire weight of the mounting, and on account of the position of the lower weight bearing member, in advance of the plane of the lenses, the mounting, when properly adjusted, should be balanced upon the face so as to steady it in place without the use of any supplemental anchoring devices when the head is held erect. This adjustment of the lower guard is attained either by the use of a plurality of notches or like devices, as shown for instance in Fig. XII, or may be attained entirely by bending in and out, sidewise, or torsional twisting of the bearing blade or parts thereof, and of the reduced neck 22 provided for this purpose, the competent adjuster bending these various ductile parts until the exact fit is attained. The parts are made sufficiently pliable to permit of this adjustment, and at the same time are rigid enough to retain the adjustment under ordinary service conditions. The advantage of this should be readily apparent, as it will be seen that the mounting when fitted will fit at but one point on the nose, and thus the wearer is sure at all times of getting the mounting in exactly the right position on his face, a result difficult of attainment hitherto in the use of glasses held on the nose by spring pressed clamps or the like, and a result, the importance of which cannot be over-estimated, particularly in astigmatic or other similar eye troubles. The mounting having been properly fitted, as above pointed out, the next step is the correct adjustment of the supplemental anchoring devices so that the same will fit into the socket at the junction of the nose and eye brows and will so engage the flesh and loose skin at this point as to hold the mounting against any rolling or tilting forward and falling off the face, this being the natural loosening movement of a properly adjusted mounting. To prevent this movement the upper guard arm is then adjusted by bending of the loop therein, by twisting of the offset 16 thereof, or the like, or by partial rotation and locking in such forms as shown in Fig. XII for example, the idea being to secure the best possible engagement of the pad or anchoring member 17 with the nose, that is to say, the engagement where this pad will best fit into the aforementioned socket and engage the loose flesh to grip the same with a minimum of spring pressure, a loose pad being preferably employed for

this purpose, as it will better bite into the flesh and resist forward tilting or rolling movement, although an ordinary rigid pad may be employed if preferred by the particular wearer or fitter of the mounting.

From the foregoing description taken in connection with the accompanying drawings, the construction of my improved mounting should be readily apparent, and it will be seen that I have provided a novel construction of this character in which the lower guard 7 may be readily adjusted to fit the side of the nose and bear most of the weight of the mounting, while the upper or supplemental guard member, which is preferably disposed somewhat rearwardly of the first mentioned guard member, serves to grip the flesh at the upper part of the nose and anchor the mounting against tilting movement, and consequently I have provided an extremely satisfactory, adjustable and practical construction which may be readily assembled, in which the various parts are interchangeable, and which should prove extremely efficient for the desired purpose.

I claim—

1. The combination with a support having an aperture formed therethrough, of a lower non-rotatable guard, an upper movable guard, a bearing for the latter, actuating means for the movable guard, and means engaged in the aperture in the bridge

for securing the various parts in position, substantially as described. 35

2. In a spectacle mounting, the combination with a supporting portion, of a pivot carried thereby, a pair of independent guards mounted upon the pivot, means for locking one of said guards against rotation 40 on the pivot, and means for rocking the other guard on the pivot.

3. In a spectacle mounting, the combination with a supporting portion, of a pivot carried thereby, a lower guard embracing 45 the pivot and locked against rotation thereon, an upper guard rotatably mounted on the pivot and a spring carried by the pivot for actuating said upper guard.

4. In a spectacle mounting, the combination with a support, of a guard interlocking with the support, a pivot member having a portion clamping said guard in interlocking engagement with the support, and a second guard rotatably mounted on the pivot, 55 means for manually operating said second guard in one direction and means for automatically actuating it in the opposite direction.

In testimony whereof I affix my signature 60 in presence of two witnesses.

JOEL C. WELLS.
